BLANKET

Attilio Harold Zayotti, Palmyra, N. J., and Earl Reinert Reber, Philadelphia, Pa.

Application January 3, 1936, Serial No. 57,372

1 Claim. (Cl. 5—334)

This invention relates to a blanket and has particular reference to a blanket suitable for use by the violently insane.

Ordinary blankets cannot be used in insane asylums since violent inmates readily destroy them. It is the object of the present invention to provide a strong blanket which, though it has the flexibility and provides the warmth of an ordinary blanket, cannot be readily destroyed. 5 This object is attained by so constructing the blanket that it offers no chance for a grip which would permit destructive tearing. It has been found that blankets so constructed stand up for periods far exceeding the periods of life of ordinary blankets.

The improved construction will be apparent from the following description read in conjunction with the accompanying drawing, in which:

Fig. 1 is a plan view showing a corner of the 20 improved blanket; and

Fig. 2 is a perspective view partly in section and partly broken away to specifically show the constructional details which lead to the attainment of the desired object.

25 The blanket comprises an intermediate ply 2 of strong fabric such as canvas or equivalents, for example, duck, etc. Preferably this canvas or duck, though strong, is of such weight that the resulting blanket is readily flexible and, in 30 respect to handling or use, differs little from conventional blankets.

The intermediate ply 2 is faced with plies 4 and 6 of conventional blanket material, for example, a heavy woolen material which will provide the necessary warmth and softness. This material alone is not particularly strong in its 35 resistance to tearing or destruction.

Tapes 8 of woven type and of a comparatively heavy nature are inserted, as indicated in the 40 drawings, between one of the outer plies and the intermediate ply at the edges thereof and all four plies thus resulting are stitched together by non-raveling overseaming of a type which does not involve chain stitches and hence cannot be 45 destroyed readily. The type illustrated in Fig. 2, for example, comprising three threads, can only be destroyed with considerable difficulty. Strong heavy thread is, of course, desirable, so that destruction by the teeth cannot be readily 50 accomplished.

In order to further reinforce the edges, lines

of lock stitches, as indicated at 12, are run parallel to the edges through the plies and tape and interiorly of the tape to insure that the plies all along the edge are in close contact with each other, thus affording a reinforced condition which 5 makes it practically impossible to start a tear from the edge of the blanket.

Besides the above stitching, the entire surface of the blanket is covered by crisscross lines of lock stitches, as indicated at 14, which lines are 10 so run as to leave only relatively small areas which are not tacked down by the stitches. Preferably the lines of stitches are run at right angles, leaving square or rectangular areas which are preferably less than three inches on a side. 15 Desirably the areas are even smaller. As a result, substantial separation of the outer plies from the intermediate canvas ply is impossible and any grip on the outer fabric can only be attained between the tips of the fingers, it being 20 impossible to grip a portion of the fabric within the hand. As a result, it is difficult to start a tear inwardly of the edges.

Destruction of the blanket described substantially necessitates either the use of some mechanical means which, of course, should not be available, or destruction of the stitching. All of the stitching should be of non-raveling character and of such heavy, strong thread that breaking, even by the use of the teeth, is impossible. 25

It will be clear that variations may be made in the specific embodiment of the invention without departing from the advantageous features which are herein claimed.

What we claim and desire to protect by Letters 35 Patent is:—

A blanket comprising outer plies of facing fabric, an intermediate ply of strong fabric such as canvas or the like, the edges of said plies being substantially aligned, tapes extending along said edges inside the outer plies, non-raveling overseaming binding the edges of the plies and the tapes, closely arranged lines of lock stitches running along the edges and penetrating the plies and tapes, and crisscross lines of lock stitches 40 through the plies throughout the entire blanket, the last lines being relatively closely arranged 45 to prevent substantial spacing of the outer plies from the intermediate one.

ATTILIO HAROLD ZAYOTTI. 50
EARL REINERT REBER.
